FIG. 3.

UNITED STATES PATENT OFFICE.

JOHN R. PHEENEY, OF OWATONNA, MINNESOTA.

SIGNAL APPARATUS.

SPECIFICATION forming part of Letters Patent No. 334,980, dated January 26, 1886.

Application filed June 30, 1885. Serial No. 170,315. (No model.)

To all whom it may concern:

Be it known that I, JOHN R. PHEENEY, a citizen of the United States, residing at Owatonna, in the county of Steele and State of Minnesota, have invented certain new and useful Improvements in Signal Apparatus, of which the following is a specification, reference being had therein to the accompanying drawings.

10 Figure 1 is a perspective view, with some portions of the case removed to show the interior construction and parts of this device. Fig. 2 is a sectional view on line $x-x$, Fig. 1. Fig. 3 is a horizontal sectional view on line $y-y$, Fig. 1. Fig. 4 is a front elevation, the front plate being removed. Fig. 5 is a detail showing the glass, &c., on the right-hand side of this device.

15 This device belongs to that class of inventions known as "signals" or "signal-lamps;" and the novelty in the present instance consists in the construction and combination of all the parts, whereby a very perfect and effective means for signaling is produced, all as will 20 now be more fully set out and explained.

25 In the accompanying drawings, A denotes the case or box, which may be set on its bottom or confined to a post by means of its rear recess, a , and straps, or in any suitable or desirable way located and fixed in any place or 30 position for the use required. Inside this case, and on the lower part, is placed the lamp B, of suitable shape and size, so that its flame comes between and nearly in the foci—that is, 35 the smaller ends—of the conical reflectors C, one on each side. These reflectors are held in place in any convenient way. They are now shown as sustained at the front or larger ends by standards e, one on each side of each 40 reflector, while at their inner and smaller ends they are connected together at a point on each side.

45 The smoke, heat, &c., from the lamp escape through the top of the case A by the pipe a' , directly over it. This pipe preferably has a hood to close it against rain, wind, and dust as much as can well be done.

50 In the right side wall of the case A is a glass, D, placed immediately in front of one of the large or outer ends of the reflector C, and in like manner in the opposite or left-hand side of the case is the glass D'. Preferably each

of these glasses is set in a slide, a^2 , moving in guideways a^3 on the outside of the case; but the mere detail of this arrangement is of no great moment so long as the glasses are so placed that they can be easily washed or removed, or, when broken, replaced.

55 On each side, and between the ends of the reflector and the glass are the signals E and F. These are made of round frames e and f , the one set, by its arms e' , connected to the horizontal shafts G, which pass from side to side of the parts A' A² of the case, each of which forms one side of recess a , and the other in like manner, by its arms f' , to the shafts H, which also pass from side to side of the parts A' A². Each of the frames e and f has a colored cloth or glass over or in it, that color in e being different from that in f , but those in both 70 frames e being alike; also those in both frames f are alike. There may be as many of these frames on each side as are desired, the corresponding ones on each side having same colors; but for all ordinary uses I have found 75 that two different colors on each side, as now shown, will answer.

70 To operate the shafts G and H so as to cause either color or signal to be displayed by this device, there is an arm, g, on the end of the shaft G and outside the case. By this the signal E can be lifted from or let down before the large end of the reflector, and thus the colored glass or cloth on said signal will be displayed. The spur-wheel g' on said shaft G 85 meshes with spur-wheel h on shaft H, and these are so arranged that when signal E is raised the gears operate to turn shaft H and throw down the signal F before the lamp and reflector, and vice versa. It is preferable that 90 the frame e should be weighted, as now shown at e^2 . This construction will allow the signal E to act automatically in its downward movement when the chain I is released. The construction of these operative parts is the 95 same on each side. To the outer ends of arms g may be attached cords or chains I, which pass over pulley K and lead to any desired position where the watchman can by means of them easily operate the signals on both or 100 either side. The outer ends, h' , of shaft H may be adapted for a key, or may by a handle be operated independently.

In this device is provided a simple, cheap,

easily-operated, and excellent signaling apparatus. For instance, the signal being placed at a railroad depot or station convenient to the track, one side facing up and the other down the track, the watchman can readily signal the trains incoming or approaching from either side, and can show to each of them either the "danger" or "safety" signal, as may be necessary. This is readily done, as the signals on each side are independent of each other.

Access to the interior of the case can be had by removing the front slide, a^4 , but this can be as well accomplished by having one side of the case hinged, and by other merely mechanical changes in the structure of the parts of the case and their adjustment together. Instead of a lamp, gas may be used.

I am aware that heretofore signal devices have been used for the same purpose, and do not broadly claim that I have invented more than a very simple and very effective means for gaining these general ends.

It will be noted that I use but a single lamp or flame.

Having now described my invention, what I consider new is—

1. The case A, recessed at a and having signals E and F, connected, as described, with shafts G and H, and reflectors C and lamp B, all combined as described.

2. In a signal apparatus, the weighted frame e , having a suitable color, its arm e' and shaft G, having spur-wheel g' , combined with the signal-frame f , arm f' , and shaft H, having spur-wheel h , all combined and operating as described.

3. In the case having smoke-exit pipe, the combination of the lamp and reflectors with the signals and shafts and their connecting spur-wheels, and the chains and pulleys by which the movable parts are operated, all as described.

In testimony whereof I affix my signature in presence of two witnesses.

JOHN R. PHEENEY.
